PATTERN MECHANISM FOR DOBBY LOOMS

Ivey C. Morris, Lowell, N. C.

Application December 26, 1950, Serial No. 202,697

10 Claims. (Cl. 139—71)

1

This invention relates to looms and more especially to improvements in the pattern mechanism for dobby looms and including means for decreasing the number of links or bars on the usual pattern chain which may normally be required for controlling a fabric pattern which has a plurality of different type weaves therein.

Heretofore, in many instances, it has been necessary to provide a chain link or bar for each pick in the pattern, even though the weave might repeat itself every few picks, thus requiring a very long pattern chain to operate this pattern mechanism. The space taken up by a very long pattern chain and the cost of constructing the same makes a short pattern chain very desirable.

It is therefore an object of this invention to provide an improved pattern mechanism for a dobby head comprising a pattern chain having a plurality of link bars therein for controlling the head, with means for moving the pattern chain forwardly or rearwardly for a predetermined number of picks and means for also stopping the pattern chain for a predetermined number of picks. By using this type of pattern mechanism the same chain bars may be used over and over in a repeat weave thereby allowing pattern chains which are normally of considerable length to be shortened to a minimum number of bars or links.

It is another object of this invention to provide an improved pattern mechanism for a dobby head which includes means for controlling a plurality of different type weaves in a fabric comprising an endless bar chain with a group of bars therein for each type of weave in the fabric, alternate weaves requiring oscillatory motion of the pattern chain and other weaves requiring forward motion of the pattern chain.

Some of the objects of the invention having been stated, other objects will appear as the description proceeds, when taken in connection with the accompanying drawings, in which—

Figure 1 is a front elevation of a dobby head mechanism showing the invention secured thereto and showing the same attached to a part of a loom;

Figure 2 is an enlarged fragmentary vertical sectional view taken substantially along the line 2—2 in Figure 1;

Figure 3 is a side view of the dobby head mechanism looking at the right-hand side of Figure 1;

Figure 4 is an enlarged fragmentary plan view with parts in section taken substantially along the line 4—4 in Figure 3;

Figure 5 is an isometric view of a portion of

2

fabric, the weaving of which may be controlled by the improved pattern mechanism;

Figure 6 is a schematic vertical sectional view taken substantially along the line 6—6 in Figure 5;

Figure 7 is an enlarged fragmentary elevation looking substantially along the line 7—7 in Figure 1.

Referring more specifically to the drawings, 10 the numeral 10 designates the side frame of a loom on which this improved dobby head pattern mechanism broadly designated at 11 is adapted to be mounted at its lower end and its upper end being suitably secured to a conventional loom arch 12. The pattern mechanism 11 comprises a pair of side frames 13 and 14 in which is journaled a suitable rocker shaft 15. Suitably secured to the right-hand end of the rocker shaft 15, in Figure 3, is a rocker 16 which has pivotally connected to the upper and lower ends thereof, connecting links 20 and 21 which are pivotally connected to the right-hand ends of upper and lower dobby knives 22 and 23.

The left-hand ends of the dobby knives 22 and 23 (Figure 3) have similar connecting links 24 and 25 pivotally connected thereto which extend to the left in Figure 1 and are pivotally mounted on the respective upper and lower ends of a driving rocker 26, fixedly mounted on the left-hand end (Figure 3) of the rocker shaft 15. The driving rocker 26 has an outwardly extending arm 27 to which the upper end of a downwardly extending dobby connecting rod 31 (Figures 1 and 3) is pivotally connected as at 28. This rod 31 is oscillatably mounted at its lower end on a conventional dobby crank, not shown, which is fixedly mounted on one end of the conventional main cam shaft of the loom.

It is thus seen that, as the loom is in operation, the main cam shaft rotates the dobby crank causing the connecting rod 31 to move up and down in Figures 1 and 3 to rock the rockers 16 and 26 along with the rocker shaft 15 to cause the upper and lower dobby knives 22 and 23 to move along slots 32 and 33 in the side frames 13 and 14. Disposed between the side frames 13 and 14 of the pattern mechanism 11 is a transversely disposed shaft 34 (Figures 1 and 6) around which the lower ends of a plurality of dobby jacks 35 are adapted to pivot. Each of these dobby jacks 35 has a slot 36 therein in which a transversely disposed shaft 37 is adapted to act as a stop.

Although all of the dobby jacks are substan-

cially the same one of them is indicated at 35a and the rest of them are indicated at 35 for purposes to be later described. Each of the dobby jacks 35 and 35a has a plurality of notches 43 in the upper end thereof in which one end of connecting links 41 are adapted to be supported, the other ends of these connecting links 41 being connected to conventional loom harness not shown. The first dobby jack 35a in Figure 1 is peculiar in that it is used to control the improved pattern mechanism and therefore does not have a connecting link 41 attached to its upper end but has a tension spring 42 connected thereto at one end, the spring's other end being connected to a suitable spring anchor 43 fixedly mounted on the loom arch 12.

Each of the dobby jacks 35 and 35a has a lever 45 pivotally mounted on an intermediate portion thereof, as at 44 (Figure 6). The upper end of each lever 45 has pivotally connected thereto, as at 46, a hooked arm 47 which at times is adapted to be engaged by the upper dobby knife 22. The free ends of these hooked arms 47 are normally held out of engagement with the reciprocating dobby knife 22 by means of corresponding vertically disposed rods 50, the upper ends of which contact and support the lower intermediate portions of these hooked arms 47 so the upper dobby knife 22 will not engage the hooks of certain of the hooked arms 47 as it reciprocates in the slots 32 of the side frames 13 and 14.

The lower end of each of the rods 50 rests on the left-hand end of a dobby finger 51 (Figure 6) which is pivoted intermediate its ends upon a transversely disposed shaft 52. The right-hand end of the dobby finger 51 normally rests upon a transversely disposed supporting bar 53 which spans the distance between the side frames 13 and 14. The lower ends of the levers 45 have pivotally connected thereto, as at 54, corresponding hook arms 55 which are similar to the hooked arms 47 and each of which is normally held out of engagement with the lower dobby knife 23 by an uprising portion 56 of a dobby finger 57, the right-hand end of which also normally rests on the supporting bar 53.

By referring to Figure 6 it will be observed that, as the right-hand end of the dobby finger 57 is raised the hooked arm 55 will be lowered to allow the hook portion of the hooked arm 55 to engage the lower dobby knife 23 as it moves from left to right in Figure 6. Thus, the lever arm 45 will be moved in a counter-clockwise direction to move the dobby jack 35 associated therewith in a clockwise direction to also cause one of the connecting links 41 to be moved from left to right, in Figure 1, to thereby raise certain of the loom harnesses to which it is connected. This is a conventional operation in the dobby head mechanism.

In a like manner, if the right-hand end of one of the dobby fingers 51 is raised, the vertically disposed rod 50 will be lowered to thereby lower the hooked arm 47 so that it may be engaged and moved to the right in Figure 6 by the upper dobby knife 22 to thus move the associated lever 45 along with its associated dobby jack 35 in a manner identical to the manner just described.

Referring to Figure 1, it will be noted that there is mounted below this dobby mechanism an oil guard 60 which extends downwardly and below the dobby jacks 35 and is fixedly mounted between the side frames 13 and 14. This oil guard is for the purpose of preventing oil and dirt

from the dobby mechanism from getting onto the fabric.

The dobby fingers 51 and 57, there being one of each for each of the dobby jacks 35, are actuated by suitable pattern pins 61 fixedly mounted in a plurality of pattern chain bars 62 which are linked together to form a pattern chain broadly designated at 91.

The pattern chain 91 is mounted on a fluted 10 roller 92 (Figures 3 and 6) fixedly mounted on a transversely disposed shaft 93, said shaft having its ends journaled in bearings 94 and 95 on the lower portions of the side walls 13 and 14, respectively (Figure 3). The right-hand end of 15 the transversely disposed shaft 93 in Figure 3 has a hand wheel 96 fixedly mounted thereon, the purpose of which is to allow an operator to move the pattern chain along with the fluted roll 92 and the transversely disposed shaft 93 for adjusting the pattern.

The opposite end of the transversely disposed shaft 93 also has a hand wheel 100 fixedly mounted thereon and fixedly mounted between this hand wheel 100 and the side frame 13 are 25 first and second pattern chain driving ratchet wheels 101 and 102 which are parts of the present invention. The parts heretofore described, unless otherwise noted, are conventional parts of a dobby loom and it is with these parts that the 30 present invention is adapted to be associated.

The pattern chain driving ratchet wheels 101 and 102 are adapted to, at times, be driven by respective first and second ratchet wheel driving arms or pawls 103 and 104 respectively. 35 These ratchet wheel driving arms 103 and 104 extend upwardly and to the left in Figure 1 and have their upper ends fixedly mounted in block 107, oscillatably mounted on one end of a stub shaft 110 (Figure 3), the other end of which is 40 fixedly mounted, as by welding, on a horizontally extending support bracket 111, suitably secured to the lower portion of the driving rocker 26 as by screws 112.

The first dobby jack 35a is in this instance, the dobby jack closest to the side frame 13 of the dobby head and has fixedly mounted on the lower end thereof, as by welding, an angle bracket 113 having plate 114 adjustably mounted thereon as by screws 115 (Figure 7). Suitably secured on the adjustable plate 114, as by welding, is one end of a stub shaft 116, its other end having oscillatably mounted thereon a driving pawl 117 adapted to rest on and, at times, drive a ratchet wheel 120 rotatably mounted on a stub shaft 121 and being held thereon by a washer 122 and a nut 123. The inner end of the stub shaft 121 is suitably secured, as by welding, to a support bracket 127 secured to the side frame 13 by any suitable means, such as screws 128.

The ratchet wheel 120 has integral therewith and on the back side thereof, in Figure 1, a cam member 124 which engages the lower end of a control lever 126. The control lever 126 is oscillatably mounted intermediate its ends on a stub shaft 130 fixedly mounted in the side frame 13 of the dobby head 11 and its upper end has one end of a control cable or cord 131 fixedly connected thereto and extending to the right in Figure 1 through a guiding wire 132 and its right-hand end being fixedly connected to the upper end of a pin 133. The lower end of the pin 133 is fixedly mounted, as by a pressed fit, in a collar 136 (Figure 4) fixedly mounted on a horizontally disposed shaft 137, the opposed ends of which

are oscillatably mounted in a substantially U-shaped bracket 138.

Endwise movement of shaft 137 is prevented by a pair of collars 142 and 143 fixedly mounted on opposed ends of the shaft 137. The right-hand leg of the substantially U-shaped bracket 138 extends inwardly in Figure 4 to the side frame 13 and is suitably secured thereto, as by a bolt 144, and has the lower end of the guide wire 132 fixedly mounted thereon in any suitable manner such as by welding. Mounted around the horizontally disposed shaft 137, between the collar 136 and the right-hand leg of the substantially U-shaped bracket 138, is a torsion spring 146, one end of which is secured to the right-hand leg of the substantially U-shaped bracket 138 the other end of which is fixedly mounted around the lower portion of the pin 133. The purpose of this torsion spring 146 is to normally urge the horizontally disposed shaft 137 along with the pin 133 in a clockwise direction in Figure 1.

Fixedly mounted on the horizontally disposed shaft 137, between the collar 136 and the left-hand leg of the U-shaped bracket 138 in Figure 4, is a collar 150 having fixedly mounted therein one end of a second pin 151 which extends at an angle relative to the first pin 133 and to the left in Figure 1 and has fixedly mounted on its outer end one end of a control cable or cord 152. This control cable 152 extends downwardly in Figure 1 and is connected to the ratchet wheel driving arm 103 adjacent its free end.

Connected to the upper end of the first pin 133 is one end of a control cable or cord 155 which extends to the left in Figure 2 and passes over a grooved pulley 156 (Figures 1 and 2) and then extends downwardly therefrom, its lower end being fixedly connected to the adjustment plate 114 on doby jack 35a, by any suitable means such as a screw 160. By referring to Figure 2, it will be noted that the grooved pulley 156 is rotatably mounted on one end of a stub shaft 157, the other end of which is suitably secured, as by welding, to a support bracket 158 suitably secured, as by a screw 159, to the loom arch 12.

In operation, as the main crank shaft of the loom rotates along with the doby crank, the doby connecting rod 31 will be caused to move up and down to thereby rock the rocker 26 and through the connecting links 20, 21, 24 and 25 move the upper and lower doby knives 22 and 23 along the slots 32 and 33 in the side frames 13 and 14 to pull any of the hooked arms 47 or 55 outwardly that may have been lowered because of the pattern pins 61 coming into contact with the corresponding doby fingers 51 and 57 to operate the doby jacks 35 according to the desired pattern. It is obvious that the driving rocker 26 is caused to rock as the loom weaves and the stub shaft 110 mounted on bracket 111 on the rocker 26 will cause the first ratchet wheel driving arm 103 to drive the first ratchet wheel 101 to thereby move the pattern chain in a counter-clockwise direction in Figure 1 in a step-by-step manner while a certain pattern is being made in the cloth.

In order to increase the range of the pattern chain without increasing the effective length of the pattern chain 91, a special pair of pins 61a are provided in at least one of the pattern bars 62 (Figure 3) which, when they reach the index point directly under the doby fingers 51 and 57 corresponding to the first doby jack 35a,

will cause the hooked arms 47 and 55 to be lowered so that their hooked portions will be engaged by the doby knives 22 and 23 and be moved outwardly thereby to thus cause the doby jack 35a to move a partial revolution clockwise about the transversely disposed shaft 34. It is thus seen that, as the doby jack 35a is moved in a clockwise direction in Figures 1 and 6, the angle bracket 113 and its associated driving pawl 117 will move from left to right in Figure 1 and the pawl will engage the next tooth on the ratchet wheel 120. Thus, upon this doby jack 35a subsequently being moved in a counter-clockwise direction, the ratchet wheel 120 will be racked one tooth.

As the doby jack 35a is moved in a clockwise direction in Figures 1 and 6, the control cable 155 will be slackened and the pin 133 will move in a clockwise direction in Figure 1, because of the torsion spring 146 (Figure 4), to also move the pin 137 in a clockwise direction to thereby tighten the control cable wire 152. This will move the first ratchet wheel driving arm 103 out of engagement with the first ratchet wheel 101 and move the second driving pawl 104 into engagement with the second ratchet wheel 102 to thereby reverse the direction of rotation of the pattern chain 91 so it will travel in a clockwise direction in Figure 1 upon the next clockwise movement of the rocker 26, which will then move the previous bar 62, which does not have any pins 61a thereon, into indexing position.

Now, since the bar 62 that is then under the index point of the doby fingers 51 and 57, that control the doby jack 35a, does not have the special pins 61a thereon, the hooked arms 47 and 55 will not engage the upper and lower doby knives 22 and 23 and the doby jack 35a will be pulled in a counter-clockwise direction against the transversely disposed pin 37 by the tension spring 42 on its upper end thereof to thereby tighten the control wire 155 and pull the pin 133 in a counter-clockwise direction in Figure 1 and, through intervening connections, slacken the control wire 152 and allow the first ratchet wheel driving arm 103 to again come into engagement with the first ratchet wheel 101 to move the second ratchet wheel driving arm 104 out of engagement with the second ratchet wheel 102. This will again cause the pattern chain 91 to move a step in rotation in a counter-clockwise direction upon the next clockwise movement of rocker 26, to again bring the pattern bar 62 which has the special pins 61a thereon to the index point directly under the doby fingers 51 and 57.

Thus, upon the next stroke of the rocker 26 in the manner previously described, the pattern chain 91 is moved one step in rotation in a clockwise direction, and the jack 35a also causes the ratchet wheel 120 to move another step in rotation.

This action of weaving a certain pattern using only two pattern bars 62 on the pattern chain 91 may continue for as long as desired and, in this case, for as long as the teeth in the ratchet wheel 120 are racked until the high point of the cam surface 124 engages the lower end of the control lever 126 to move the control lever 126 in a counter-clockwise direction thereby tightening the control cable 131 and causing the pin 133 to be moved in a counter-clockwise direction in Figure 1 to override the mechanism of the doby jack 35a and slacken the control

wire 152 to allow the first ratchet wheel driving arm 103 to move into engagement with the first ratchet wheel 101 twice in succession to drive the pattern chain 91 in a counter-clockwise direction in Figure 1 until the special pins 61a have passed the index point.

At this time, the high point of the cam surface 124 will be out of engagement with the lower end of the control lever 126 to permit the control lever 126 to move in a clockwise direction to thereby slacken the control cable 131. However, this would not allow the tension spring 146 to move the pins 151 and 133 in a clockwise direction in Figure 1, as would normally be the case, because there are no special pins 61a under the dobby fingers 51 and 57 and, therefore, the dobby jack 35a will remain in the position shown in Figures 1 and 6 and the control cable 155 will be tightened to hold the pins 133 and 151 in the position shown in Figure 1.

The control cable 152 will then be slack and thereby allow the first ratchet wheel driving arm 103 to remain in engagement with the ratchet wheel 101 to drive the pattern chain in a counter-clockwise direction in Figure 1 until another special pattern pin 61a is positioned at the index point under the dobby fingers 57.

In Figure 3 it will be observed that a pair of special pattern pins are disposed on each of a pair of alternate bars 62. This would merely cause the cycle of ratchet wheel 120 to be repeated. In Figure 5 there is shown a portion of fabric F which has basic areas 165 and striped weftwise extending areas 166 therein, the pattern of areas 166 being the same from pick to pick, or may vary in alternate picks.

Thus, the areas 166 may be woven by repeats of the patterning on two adjacent bars 62 on the dobby mechanism, these bars 62 including one of the bars having pins 61a thereon and the adjacent bar that does not have the pins 61a thereon as heretofore described.

The description and operation as heretofore described has been made based upon a double-indexing dobby head, that is, two picks are woven while the bar having the pins 61a thereon is in operative position and, upon the ratchet wheel being engaged to reverse the direction of movement of the pattern chain, thus positioning a bar which does not have the pins 61a thereon in operative position, two more picks are woven, this being repeated with each step in movement by the pattern chain in opposite directions.

Now, if the operator desires to weave a predetermined number of picks wherein the same harnesses are to be raised and lowered with successive pairs of picks, the pawl 104 could be removed from the block 107 and the patterning on the pattern chain 91 would be so arranged that, with each stroke of the rocker 26 in a clockwise direction in Figure 1, a stroke in a clockwise direction is also imparted to the special jack 35a. Thus, the tension spring 146 (Figure 4) on the shaft 137 would cause the pins 133 and 151 to move upwardly or in a clockwise direction in Figure 1 to thus raise the pawl 103 out of engagement with the corresponding ratchet wheel 101. Thus, the ratchet pawl 103 would fail to engage the next succeeding tooth in the ratchet wheel 101.

In the next succeeding stroke of the rocker 26, in a counter-clockwise direction in Figure 1, the special jack 35a also moves in a counter-clockwise direction to again move the pawl 103 into engagement with the ratchet wheel 101. How-

ever, since the pawl 103 engages the ratchet wheel 101 only as the rocker 26 moves in a counter-clockwise direction, a step in rotation will not be transmitted to the pattern chain 91 or roller 92 because the pawl 103 is lowered against the ratchet wheel 101 as jack 35a moves to the left and therefore fails to engage another tooth on the ratchet wheel 101. The number of picks which may be repeated in this manner is determined by the number of teeth in the sprocket wheel 120.

It is thus seen that the special jack 35a will be caused to move in one direction about its axis with alternate picks by the loom and will be caused to move in the opposite direction with each pick between said alternate picks to thus cause a step in rotation to be imparted to the ratchet wheel 120 with alternate picks by the loom. Thus, the high point on the cam 124 will finally engage the lower end of the control lever 126 to move the pins 133 and 151 in a counter-clockwise direction in Figure 1 so that, as the rocker 26 moves in a counter-clockwise direction, after the desired number of picks having been woven by the loom, the ratchet pawl 103 will then engage the next succeeding tooth in the ratchet wheel 101 to cause another step in rotation to be imparted to the pattern chain 91 and to thereby again condition the pattern chain 91 for normal patterning operations. It is evident that the rod 58 would have to be removed or the free end of one dobby finger would have to be lowered while the other would be raised so the rocker 26 would cause jack 35a to oscillate with and in the same direction as the rocker 26.

Although a double indexing dobby head is shown in the drawings, it is to be understood that the apparatus may be used equally as efficiently with a single indexing dobby head.

It is thus seen that I have provided a means for driving the pattern chain in a conventional step-by-step manner in a counter-clockwise direction in Figure 1 and also moving the pattern chain one step in rotation in a counter-clockwise direction and the next step being one step in a clockwise direction for a predetermined number of picks, as desired, to thereby weave particular patterns to, thus, substantially shorten the length of the pattern chain that would ordinarily be required. The length of time that the pattern chain is oscillated or moved in one direction for one step and then reversed for another step is limited only by the size of the ratchet wheel 120 and the number of teeth therein. This ratchet wheel 120 may be replaced with a similar ratchet wheel of a different number of teeth according to the desired pattern.

In the drawings and specification there has been set forth a preferred embodiment of the invention, and although specific terms are employed, they are used in a generic and descriptive sense only and not for purposes of limitation, the scope of the invention being defined in the claims.

65 I claim:

1. An improvement in the dobby head of a loom, said dobby head having dobby jacks and also having a rocker and also having pivoted hooked arms associated with each dobby jack and also having means on the rocker engageable by said hooked arms for imparting movement to the corresponding dobby jacks and also having rotatable pattern means for controlling the operation of the hooked arms for determining the 70 dobby jacks to be operated by the means on the 75

rocker according to a desired pattern, said improvement comprising a block pivotally mounted on the rocker and adapted to move therewith and having first and second spaced ratchet pawls extending therefrom, a first and a second oppositely directed ratchet wheel operatively associated with said rotatable pattern means, the free ends of the first and second pawls being disposed astride and coinciding with the corresponding first and second ratchet wheels, a special doby jack adapted to be oscillated in response to said pattern means, a normally upwardly biased spring loaded member disposed above the free ends of said pawls, a pliable connection between the normally upwardly biased member and said pawls, a connection between said special doby jack and the spring loaded member normally permitting the first pawl to ride in engagement with the corresponding ratchet wheel for imparting step-by-step rotation to the pattern means in one direction during operation of said rocker, said connection between the special doby jack and the spring loaded member being operable with the special doby jack to thereby permit the spring loaded member to move upwardly to move the second ratchet pawl into engagement with the second ratchet wheel upon the pattern means affecting the special doby jack to cause the same to move in one direction to thereby cause the pattern means to be alternately rotated a step in a reverse direction.

2. In a doby head for looms having doby fingers, doby knives, doby jacks and a rocker operatively connected to the doby knives for imparting reciprocatory motion thereto, a roller having a pattern chain mounted thereon and a first movable means for imparting movement to the roller, an improved means for controlling the engagement and disengagement of said movable means comprising a ratchet wheel rotatably mounted on the doby head, a spring loaded special doby jack normally biased in one direction, a ratchet pawl carried by said special doby jack and engaging said ratchet wheel, cam means operatively connected to the ratchet wheel, a second movable means disposed adjacent the cam means, mechanical connections between said second movable means disposed adjacent the cam means and the first movable means associated with the roller and means responsive to the patterning on said pattern chain for moving said special doby jack away from its spring means momentarily and then for releasing the special doby jack to permit its spring means to reverse the direction of movement thereof for imparting a step in rotation to said ratchet wheel and said cam means having a high point thereon, whereby upon a revolution being imparted to the ratchet wheel, the high point of said cam means will engage the second movable means disposed adjacent the same for disengaging the first movable means which drives said roller to thus stop movement thereof.

3. An improvement in a doby head for looms having doby fingers, doby knives, doby jacks and a rocker operatively connected to the doby knives for imparting reciprocatory movement thereto and also having a roller provided with a pattern chain mounted thereon and also having a member pivotally mounted on the rocker having a pair of pawls projecting therefrom, a pair of ratchet wheels operatively connected to the roller and said pawls being disposed on opposed sides of the ratchet wheels, said improvement comprising a third ratchet wheel rotatably

mounted on the doby head, a third pawl carried by one of said doby jacks and engaging said third ratchet wheel, a pivoted member disposed adjacent said pair of pawls and having spring means associated therewith normally urging the pivoted member away from the pawls, a cable connected to the pivoted member at one end thereof and having its other end connected to the doby jack which carries said third ratchet pawl and normally holding the said pivoted member in a position towards said pair of pawls, a connection between the pivoted member and at least one of said pair of pawls and normally permitting one of said pawls to engage the corresponding ratchet wheel to rotate the corresponding ratchet wheel in one direction upon oscillation of said rocker, means on said pattern chain for effecting movement of the doby jack having the third pawl thereon to thus permit the spring loaded pivoted member to move one of the pair of pawls out of engagement with the corresponding ratchet wheel and to move the other of the pair of pawls into engagement with the other of the ratchet wheels associated therewith for imparting a reverse step in rotation to the roller and its corresponding pattern chain, cam means operatively connected to the third ratchet wheel and means engageable by said cam means for again moving the pivoted member towards the pair of pawls to thus permit the original of said pawls to again move into engagement with the corresponding ratchet wheel to again cause the pattern chain to move in its original direction.

4. An improvement in a doby head for looms having doby fingers, doby knives, doby jacks and a rocker operatively connected to the doby knives for imparting reciprocatory motion thereto, a roller having a pattern chain mounted thereon, first and second ratchet wheels having oppositely directed teeth thereon and being operatively connected to the roller, a member pivotally mounted on the rocker and having first and second pawls projecting therefrom and being disposed on opposed sides of the corresponding first and second ratchet wheels, said improvement comprising a spring loaded member normally holding one of the ratchet pawls in a position to rotate the corresponding ratchet wheel in one direction, a cam member rotatably mounted on the doby head, means responsive to the patterning on the said pattern chain for effecting intermittent rotation of said cam member, said cam member having a low point and a high point thereon, means engaging said cam and having an operative connection between the same and the spring loaded member and being so arranged that, upon one of the points of said cam engaging the same, the pivoted member will be moved in one direction to move the other of said pawls into engagement with the corresponding ratchet wheel and, upon the other of the points of said cam moving into engagement with the means having the operative connection between the same and the pivoted member, the other of the pawls will again be moved into engagement with the corresponding ratchet wheel to thus successively advance and reverse the direction of movement of the pattern chain.

5. An improvement in the doby head of a loom, said doby head having doby jacks and also having a rocker and also having pivoted hooked arms associated with each doby jack and also having means on the rocker engageable by said hooked arms for imparting movement to the corresponding doby jacks and also hav-

ing rotatable pattern means for controlling the operation of the hooked arms for determining the dobby jacks to be operated by the means on the rocker according to a desired pattern, said improvement comprising a block pivotally mounted on the rocker and adapted to move therewith and having first and second spaced pawls extending therefrom, a first and a second oppositely directed ratchet wheel operatively associated with said rotatable pattern means, the free ends of the first and second pawls being disposed astride and coinciding with the corresponding first and second ratchet wheels, a third ratchet wheel rotatably mounted on the dobby head, a special dobby jack adapted to be oscillated in response to said pattern means and having a third pawl pivotally mounted thereon, the free end of said third pawl engaging the teeth of said ratchet wheel, a normally upwardly biased spring loaded member disposed above the free ends of said pawls, a pliable connection between the normally upwardly biased member and said pawls, a connection between said special dobby jack and the spring loaded member normally permitting the first pawl to ride in engagement with the corresponding ratchet wheel for imparting step-by-step rotation to the pattern means in one direction during operation of said rocker, said connection between the special dobby jack and the spring loaded member being operable with the special dobby jack to thereby permit the spring loaded member to move upwardly to move the corresponding second ratchet pawl into engagement with the second ratchet wheel upon the pattern means affecting the special dobby jack to cause the same to move in one direction to thereby cause the pattern means to be rotated in a step-by-step manner in a reverse direction, said third ratchet wheel having a cam surface thereon, a lever arm oscillatably mounted on the dobby head, a pliable connection between one end of said lever arm and said spring loaded member, said cam surface having a high point thereon, the end of said lever arm remote from the end having a pliable connection thereon being adapted to engage the cam surface on the ratchet wheel and said pattern means being operable upon the special dobby jack to cause the same to oscillate with certain picks by the loom to thereby cause the first and second pawls to be alternately moved into engagement with the corresponding first and second ratchet wheels to alternately impart movement to the pattern means in opposite directions and to also impart step-by-step movement to said third ratchet wheel upon each oscillation of the special dobby jack whereby, upon said high point of the cam surface moving into engagement with the corresponding end of said lever arm, the pliable connection at the other end thereof will be pulled taut to cause the spring loaded member to remain in a predetermined position to thus cause a repeated step in rotation of said pattern means in one direction to thus permit the pattern means to be ineffective upon said special dobby jack and thus resulting in continuous step-by-step movement subsequently being imparted to the pattern means in one direction until another cycle in the operation of the third ratchet wheel may be desired.

6. An improvement in the dobby head of a loom, said dobby head having dobby jacks and also having a rocker and also having pivoted hooked arms associated with each dobby jack

and also having means on the rocker engageable by said hooked arms for imparting movement to the corresponding dobby jacks and also having rotatable pattern means including a pattern chain having link bars with pattern pins thereon for controlling the operation of the hooked arms for determining the dobby jacks to be operated by the means associated with the rocker according to a desired pattern, said improvement comprising means for repeating the operation of an adjacent pair of bars on the pattern chain including a block pivotally mounted on the rocker and adapted to move therewith and having first and second spaced pawls extending therefrom, a first and a second oppositely directed ratchet wheel operatively associated with said rotatable pattern means, the free ends of the first and second pawls being disposed astride and coinciding with the corresponding first and second ratchet wheels, one of said pair of bars having special pattern pins thereon, a special dobby jack adapted to be oscillated in response to the special pattern pins on said bar, a normally upwardly biased spring loaded member disposed above the free ends of said first and second pawls, a pliable connection between the normally upwardly biased member and said pawls, a connection between said special dobby jack and the spring loaded member normally permitting the first pawl to ride in engagement with the corresponding ratchet wheel for imparting step-by-step rotation to the pattern means in one direction during operation of said rocker, said connection between the special dobby jack and the spring loaded member being operable with the special dobby jack to thereby permit the spring loaded member to move upwardly to move the second ratchet pawl into engagement with the second ratchet wheel upon the the special pattern pins being moved into operative position to cause the special dobby jack to move in one direction to thereby cause the pattern means to be rotated a step in a reverse direction.

7. An improvement in a dobby head for looms having dobby fingers, dobby knives, dobby jacks and a rocker operatively connected to the dobby knives for imparting reciprocatory motion thereto, a roller having a pattern chain mounted thereon, first and second ratchet wheels having oppositely directed teeth thereon and being operatively connected to the roller, a member pivotally mounted on the rocker and having first and second pawls projecting therefrom and being disposed on opposed sides of the corresponding first and second ratchet wheels, said improvement comprising means for holding one of the ratchet pawls in a position to rotate the corresponding ratchet wheel in one direction with movement of the rocker, a cam member movably mounted on the dobby head, means for imparting movement to said cam member in timed relation to operation of the loom and means controlled by said cam member for moving said means holding one of the ratchet pawls in a position to rotate the corresponding ratchet wheel in one direction to another position to cause the other of the ratchet pawls to rotate the corresponding ratchet wheel in the opposite direction thereby resulting in the pattern chain being advanced for a predetermined number of strokes of the rocker and to be alternately reversed as to its direction of movement for a predetermined number of strokes of the rocker.

8. An improvement in a dobby head for looms

having dobby fingers, dobby knives, dobby jacks and a rocker operatively connected to the dobby knives for imparting reciprocatory motion thereto, a roller having a pattern chain mounted thereon, first and second ratchet wheels having oppositely directed teeth thereon and being operatively connected to the roller, a member pivotally mounted on the rocker and having first and second pawls projecting therefrom and being disposed on opposed sides of the corresponding first and second ratchet wheels, said improvement comprising a spring loaded member mounted on the dobby head and normally biased to urge said pawls in one direction to thereby urge the first pawl into engagement with the corresponding ratchet wheel for imparting step-by-step movement to the pattern chain with movement of the rocker, a cam rotatably mounted on the dobby head, mechanical connections between said cam and the spring loaded member, means driven by the loom for operating the dobby head and means operatively connected to the last-named means for imparting rotation to said cam in timed relation to operation of the loom, said cam having a high point and a low point thereon, whereby, upon one of the points of said cam moving into engagement with said mechanical connections, the spring loaded member will be moved in a direction opposite to the direction in which it is biased to thus move the second pawl into engagement with the corresponding ratchet wheel for alternately imparting step-by-step movement to the pattern chain in a reverse direction.

9. An improvement in a dobby head for looms having dobby fingers, dobby knives, dobby jacks and a rocker operatively connected to the dobby knives for imparting reciprocatory motion thereto, a roller having a pattern chain mounted thereon, first and second ratchet wheels having oppositely directed teeth thereon and being operatively connected to the roller, a member pivotally mounted on the rocker and having first and second pawls projecting therefrom and being disposed on opposed sides of the corresponding first and second ratchet wheels, said improvement comprising a spring loaded member mounted on the dobby head and normally biased in one direction to cause one of said pawls to transmit step-by-step movement to the pattern chain in one direction with movement of the rocker, a third ratchet wheel rotatably mounted on the dobby head, a third pawl pivotally mounted on one of the dobby jacks and adapted to oscillate therewith for imparting step-by-step movement to the corresponding third ratchet wheel, a cam member having a high surface and a low surface thereon operatively connected to said third ratchet wheel, an oscillatable arm having one end thereof normally engaging one of the surfaces of said cam, a connection between the free end of said oscillatable arm and the spring loaded member whereby, upon the other surface of said cam engaging the oscillatable arm, the connection between the other end of the oscillatable arm and the spring loaded member will impart movement to the spring loaded member to move the other of the pawls into engagement with the corresponding ratchet wheel for imparting step-by-step movement to the pattern chain in the opposite direction.

10. An improvement in a dobby head for looms having dobby fingers, dobby knives, dobby jacks and a rocker operatively connected to the dobby knives for imparting reciprocatory motion thereto, a roller having a pattern chain provided with pattern links mounted thereon, a first ratchet wheel operatively connected to the roller, a member pivotally mounted on the rocker and having a first pawl projecting therefrom and having its free end normally resting upon the first ratchet wheel, said improvement comprising a normally upwardly biased spring loaded member disposed above the first ratchet wheel, a connection between the first pawl and the spring loaded member, a pattern controlled special jack carried by the dobby head and adapted to move in opposite directions with each pair of picks woven by the loom, a second pawl carried by the special dobby jack, a second ratchet wheel rotatably mounted on the dobby head and having a cam thereon provided with a high point and a low point, said second pawl normally resting upon said second ratchet wheel, an oscillatable lever oscillatably mounted on the dobby head and having one end thereof normally engaging the low point on said cam, a mechanical connection between said spring loaded member and the special dobby jack, another mechanical connection between the free end of said oscillatable lever arm and the spring loaded member, said connection between the special dobby jack and the spring loaded member normally moving the spring loaded member in a direction opposite from the direction in which it is biased to normally permit the first pawl to impart step-by-step movement to the ratchet wheel and the associated roller upon movement of the rocker whereby, upon said pattern means effecting operation of the special dobby jack, the dobby jack will cause its associated pawl to subsequently impart a step in rotation to the second ratchet wheel and will also permit the spring loaded member to move upwardly to lift the first pawl out of engagement with the first ratchet wheel to thus cause the patterning on a single link of the pattern chain to be effective for operating the jacks other than the special jack for a predetermined number of picks, and whereby, upon the high point of said cam engaging the adjacent end of said oscillatable lever, the mechanical connection between the free end of said lever and the spring loaded member will again cause the spring loaded member to move downwardly to again permit the corresponding first ratchet pawl to impart another step in rotation to the first ratchet wheel and its roller to thus cause the pattern chain to operate in a normal manner until operation of the special jack is again effected by the patterning on said pattern chain.
